UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SEPARABLE CONTACT DEVICE.

1,335,550.

Specification of Letters Patent. Patented Mar. 30, 1920.

Application filed June 24, 1915. Serial No. 36,006.

To all whom it may concern:

Be it known that I, REUBEN B. BENJAMIN, a citizen of the United States, residing at Chicago, in the county of Cook and State of Illinois, have invented new and useful Improvements in Separable Contact Devices, of which the following is a full, clear, concise, and exact description, reference being had to the accompanying drawing, 10 forming a part of this specification.

My invention relates to separable contact devices, and more specifically to such devices in which a binding terminal carrying member is provided with contacts for detachable 15 engagement with the contacts of a device which is electrically connected with the supply circuit.

One of the objects of my invention is to provide an improved device of this character in which the binding terminal carrying member can engage the contacts of the device connected with the feed circuit in various positions, and in which it can easily be determined which one of the binding posts 25 corresponds to the different contacts, and which is simple in construction and efficient in use.

Further objects will appear from the detailed description to follow and from the 30 appended claims.

In the drawings in which I have shown several embodiments of my invention—

Figure 1 is an axial section of a separable attachment plug embodying my invention 35 showing the manner in which the contacts are supported and engage each other;

Fig. 2 is a bottom view of the insertible portion of the plug, the cap being removed to show the relative arrangement of the contacts;

Fig. 3 is an axial section on the line 3—3 of Fig. 1 showing the manner in which the individual conductors are gripped:

Fig. 4 is a top plan view of the cap removed from the insertible portion showing the arrangement of the concentric contacts;

Fig. 5 is a bottom view of one of the insulating members of the cap showing the binding screws and the cord gripping projection;

Fig. 6 is an axial section of a modified form of cap;

Fig. 7 is an axial section showing my invention in connection with an adapter 55 whereby my improved plug cap may be

used in connection with parts of certain forms of plugs already on the market.

Fig. 8 is an axial section on the line 8—8 of Fig. 9, showing the manner in which the contacts are supported on the adapter; 60

Fig. 9 is a top plan view of the adapter showing the relative arrangement of the contacts;

Fig. 10 is a bottom view of the adapter;

Fig. 11 is an axial section showing my invention embodied in a connector in which my improved binding terminal carrying cap detachably engages a binding terminal carrying member connected with the supply circuit. 70

Fig. 12 is an axial section on the line 12—12 of Fig. 13 showing the manner in which the contacts are supported on one of the binding terminal carrying members;

Fig. 13 is a section on the line 13—13 of Fig. 11 showing the relative arrangement of the contacts;

Fig. 14 is a bottom view of one of the members of the connector; and

Fig. 15 is a section on the line 15—15 of Fig. 6, showing the manner in which the center contact is electrically connected with its binding plate.

Referring now to the drawings in detail, and first to the modification of Figs. 1 to 85

5 inclusive, I have here shown my invention in connection with a separable attachment plug comprising an insertible portion 20 which is to be screwed into a threaded shell receptacle and a cap or binding terminal carrying portion 21 provided with contacts for detachably engaging the contacts of the insertible portion 20. The insertible portion 20 comprises an inner insulating part 22 and an outer insulating part 90

23 on which are supported a threaded shell contact 24 and a center contact 25. The part 22 is recessed, as shown at 26, to receive an extension or projection 27 on the part 22 to hold the parts in their proper ele- 95

vated position. The shell contact 24 has an inwardly extending flange portion 28 which is clamped in place between the parts 22 and 23. The center contact 25 is held in place by means of a screw 29 which is threaded 100

into a nut 30 seated in a recess 31 in the part 23, the screw 29 and nut 30 also serving to hold the parts 22 and 23 together and also to hold the U-shaped spring center contact 105

32 in place on the part 23. The contact 32 110

is provided with curved tips 33 for engagement with the center contact of the cap of the plug. The shell contact 24 is provided with spring tongues 34 formed integral therewith and extending through openings 35 in the part 23 and into an annular recess 36 in the outer face of the part 23. The cap 21 comprises an insulating portion 37 for supporting the binding terminals and contacts, and an insulating portion 38 acting as a cord grip and guide, and also as a housing for the binding terminals. The insulating portions 37 and 38 are held together by means of a sheet metal shell 39. For engagement with the spring tongues 34 the insulating portion 37 is provided with an annular contact member 40 which extends into the annular recess 36 and into contact with the spring tongues 34. For engagement with the center contact 32 the portion 37 is provided with an inner annular contact member 41 concentric with the contact 40. The annular contact member 40 is provided with an inwardly extending flange 42 having a portion 43 extending inwardly farther than the rest and having an opening through which extends a bushing 44 which is riveted over the portion 43, as shown at 45, said bushing being threaded to receive one of the binding screws 46.

The insulating portion 37 is recessed, as shown at 47, to expose the portion 43 so that one can tell by inspection to which one of the binding terminals the contact 40 is connected. The portion 37 has a center projection or extension 48 for supporting the annular contact member 41. This contact member 41 comprises a knob-like portion 49 and a reduced neck portion 50 for retaining it in place on the projection 48 and also for engagement with the curved tips 33 of the contact 32 for detachably holding the contacts 41 and 32 in engagement. The center contact 41 is electrically connected with its binding terminal by means of a bent conductor plate 51 having an enlarged head 52, the contact 41 being bent inwardly below the head 52 to secure the parts firmly together and insure good electrical contact (see Fig. 15). The plate 51 has a base portion 54 forming a binding plate with which the binding screw 55 has a screw threaded engagement. The portion 37 is recessed, as shown at 56, to disclose the base 54 so that it can be determined by inspection to which one of the binding terminals the center contact 41 is connected. The insulating portion 38 is recessed, as shown at 57, to provide room for the conductors leading to the binding screws 46 and 55 and has a center opening 58 leading from the recess 57, which opening may be tapered and screw threaded, as shown at 58^a in Fig. 1, to provide a means for holding the insulation of the cord 58^b in place, or may be smooth as shown at 58^c

in Fig. 3. The insulating portion 38 is secured to the insulating portion 37 by means of a screw threaded portion 59 engaging a corresponding screw threaded portion 60 of the shell 39 which is beaded outwardly, as shown at 61, so as to be spaced from the insulating portion 37 and is flanged inwardly, as shown at 62, above the insulating portion 37.

The fact that the shell 39 is spaced from the insulating portion 37 renders the latter less liable to be cracked if the shell should strike against anything or receive a blow, than it would if it were directly in contact with the insulating portion. The insulating portion 37 has a central cord gripping projection 63 for engagement with the individual insulated conductors 64 of the cord 58^b. The insulating portion 37 is recessed, as shown at 65, to receive the binding screws 46 and 55. In wiring the cap shown in Fig. 1 the portions 37 and 38 are first separated by unscrewing the shell 39 and the portion 38. The portion 38 is then threaded onto the cord 58^b until the conductors 64 extend far enough through the opening 58 to permit them to be secured to the binding screws 46 and 55. The portion 38 can then be screwed back on the cord 58^b until the portions 37 and 38 engage each other properly, and the portions 37 and 38 can then be secured together by slipping the shell 39 over the portion 37 and threading it onto the portion 38 forcing the projection 63 into gripping engagement with the individual conductors 64. The principal purpose of the screw threads 58^a is to hold the insulation of the cord 58^b firmly to prevent its being frayed, while the purpose of the cord gripping projection 63 is to hold the cords so as to take the strain off of the binding terminals.

It will be noted that the cap 21 is held in place on the insertible portion 20 principally by the engagement of the contacts 41 and 32 as the outer contacts 40 and 34 have no curved interengaging portions. The fact that the contacts 34 and 40 have no curved interengaging portions enables the annular recess 38 to be made narrower than it could otherwise be made and still permit proper annular separation of the cap 21 from the insertible portion 20.

The circuit through the plug is from the center contact 25, through the screw 29, center contacts 32 and 41, plate 54, and binding screw 50, through the cord circuit to the binding screw 46, through the bushing 44 and contacts 40 and 34, to the threaded shell contact 24. With this plug it will be noted that after the cap has been wired the same cord terminal will always be connected electrically with the center contact 25 of the insertible portion. It will be noted that in drawing the portions 37 and 38 together to 130

clamp the individual conductors of the cord there is no relative rotation between the portions 37 and 38 which permits of the opening 58 being screw threaded to hold the insulation of the cord 58^b firmly in place.

In Fig. 6 I have shown a modification of the cap; the contacts 40, and 41, the binding screws 46 and 55 and the conducting plate 51 being, however, essentially similar to the corresponding parts of the modification of Fig. 1. In this modification the cap comprises an insulating portion 66 carrying the contacts and binding terminals, and an insulating portion 67 acting as a cord grip and cord guide, and also as a housing for the binding terminals. The portion 66 is provided with a central cord gripping projection 69 coöperating with the edge of the center opening 70 of the portion 67 to grip the individual conductors of the cord; the portions 66 and 67 have a threaded connection 68.

In wiring the cap of this modification the portions 66 and 67 are separated by unscrewing them, the portion 67 is slipped over the cord 58^b a sufficient distance to enable the individual conductors 64 to be secured to the binding screws 46 and 55, after which the portion 67 is slipped back along the cord and threaded into the portion 66 to grip the individual conductors 64.

In Figs. 7, 8, 9 and 10 I have shown my invention in connection with an adapter by means of which the cap of Figs. 1 to 6 inclusive, may be used in connection with the insertible portion of a plug of a type now in use. In this form of my invention the binding terminal carrying cap is substantially the same as that shown in Fig. 6 and comprises the contacts 40 and 41 and insulating portions 66 and 67. The adapter comprises an insulating contact carrying member 71 to which are secured the contact blades 72 and 73 which engage the contact blades 72^a and 73^a of the insertible portion of a known type of contact plug. The contact blade 73 is electrically connected with a U-shaped center contact 74, and the contact blade 72 is electrically connected with an outer contact member 75 having contact tongues 76 which extend through openings 77 into an annular recess 78 in the insulating member 71. The contact blade 72 is secured to the insulating member 71 by means of a screw 59 which extends through an opening 80 in the base portion 81 of the contact blade 72 and also extends through an opening 82 in the contact member 75 into screw threaded engagement with a bushing 83 embedded in the insulating member 71. The contact blade 73 is secured to the member 71 by means of a screw 84 which extends through the base portion 85 of the blade into screw threaded engagement with a bar 86 embedded in the insulating member 71, the

screw 84 also serving to hold the contact 74 in place. The contacts 40 and 41 of the cap engage the contacts 74 and 75 of the adapter in the same manner in which the corresponding contacts in the modification of Figs. 70 1-5 engage. The engagement between the contacts 41 and 74 and between the contacts 72 and 72^a, and 73 and 73^a is such that the cap will separate more readily from the adapter than the adapter will separate from the insertible portion so that after the adapter is put in place it will not be removed when the cap is separated from the adapter. It will thus be seen that I have provided an adapter for the insertible portion of a known type of plug which will insure that the same contact of the cap will always be brought into electrical connection with the same contact of the insertible portion; that is, if the blade 73 is electrically connected with the center contact of the insertible portion, the center contact 41 of the cap will always be electrically connected with the center contact of the insertible portion whenever the cap is secured to the adapter. 90

In Figs. 11 to 14 inclusive, I have shown my invention in connection with an insulating binding terminal and contact carrying member 89 forming part of a separable connector provided with binding screws 90 and 91 and an insulating cord guide 92 which also serves as a housing for the binding screws. The member 89 and the cord guide 92 are secured together by means of a sheet metal shell or cap 93 having a screw threaded engagement with the insulating member 89 as shown at 94. The binding screw 90 extends through an opening in a conductor plate 95 and into screw threaded engagement with a bearing 96 embedded in the insulating member 89. The conductor plate 95 is connected to the center contact 97 by means of a hollow rivet or eyelet 98. The binding screw 91 extends through an opening in a contact member 99 of sheet metal and through an opening in an insulating plate 100 of mica or other suitable material into threaded engagement with a nut 101 embedded in the member 89. The member 99 is secured to the member 89 by means of hollow rivets or eyelets 102 embedded in the member 89 and flanged over above the member 99 as shown at 103. The contact member 99 is provided with contact tongues 104 formed integral therewith and extending through openings 105 into an annular recess 106 formed in the insulating member 89. The cap shown in connection with this connector member is substantially the same as the cap shown in Fig. 6 and comprises the contacts 40 and 41 and the insulating portions 66 and 67. 115

In wiring the upper portion of the connector the member 92 is separated from the member 89 by unscrewing the shell 93 and 130

the member 92 is slipped over the ends of the leading in wires. The conductors are then secured under the binding screws 90 and 91 and the member 92 is slipped back 5 into engagement with the member 89 and the members 92 and 89 are secured together by threading the shell 93 onto the member 89. The insulating plate 100 lies between the contact member 99 and the hollow rivet 10 98 and prevents short circuiting at this point. The circuit through this connector is from the binding screw 90 through the plate 95, contacts 97 and 41 and cord circuit, to the contact 40, through the contact 15 tongues 104, to the contact member 99 and binding post 91.

Having thus described my invention what I claim as new and desire to secure by Letters Patent is:—

20 1. In a device of the class described, the combination with an insulating base having opposite faces and an annular recess in one of said faces, of a contact comprising a portion engaging the other of said faces and 25 having a portion integral with said first portion extending into said recess.

2. In a device of the class described, the combination with an insulating base having opposite faces and an annular recess in one 30 of said faces, and an opening leading from said recess to the other face, of a contact comprising a portion engaging the other of said faces and having a portion integral with said first portion extending through 35 said opening into said recess.

3. In a device of the class described, an insulating base comprising two insulating portions, a contact shell having a portion extending inward between said insulating 40 portions, one of said insulating portions having an annular recess, and a contact extending into said annular recess and electrically connected to said inwardly extending portion.

45 4. In a device of the class described, an insulating base comprising two insulating portions, a contact shell having a portion extending inward between said insulating portions, one of said insulating portions 50 having an annular recess, and a contact extending into said annular recess and electrically connected to said inwardly extending portion, said last named contact being integral with said inwardly extending portion.

5. In a contact device a substantially cylindrical insulating base, a contact carried thereby, a binding screw electrically connected to said contact extending substantially parallel to the axis of said cylinder and supported thereby, and a two-part housing for said base and screw, said housing comprising an insulating portion constituting a cord gripping member.

65 6. In a contact device a substantially cy-

lindrical insulating base, a contact carried thereby, a binding screw electrically connected to said contact extending substantially parallel to the axis of said cylinder and supported thereby, and a two-part housing 70 for said base and screw, said housing comprising an insulating portion forming a thumb piece and a sheet metal shell portion for holding said thumb piece on said base.

7. In a contact device a substantially cylindrical insulating base, a contact carried thereby, a binding screw electrically connected to said contact extending substantially parallel to the axis of said cylinder and supported thereby, a two-part housing 75 for said base and screw, said housing comprising an insulating portion forming a thumb piece and a sheet metal shell portion for holding said thumb piece on said base, said thumb piece and shell having a screw 80 threaded engagement with each other.

8. In a contact device a substantially cylindrical insulating base, a conductor supported thereby, and an annular sheet metal casing means surrounding said base and beaded outwardly from said base to provide 90 a space between said base and casing means to lessen the danger of breaking the base by jarring it.

9. In a contact device an insulating base, a contact carried thereby, and a housing for 95 said base comprising sheet metal casing means surrounding said base and beaded outwardly from said base to provide a space between said base and casing means, and a thumb piece having a screw threaded engagement with said sheet metal casing means.

10. In a connector, an insulating base comprising two insulating portions, a shell contact having a portion extending between 105 said insulating portions, a center contact supported by said base, means for holding said last contact on said base, and said insulating portions together comprising a member extending through both said insulating 110 portions, a binding terminal carrying member and contacts supported thereby for engaging said shell and center contacts respectively.

11. In a connector, an insulating base 115 comprising two insulating portions, a shell contact having a portion extending between said insulating portions, a contact carried on said base for detachably engaging another contact, and means for holding said 120 contact on said base and said insulating portions together comprising a member extending through both said insulating portions.

12. In a connector, an insulating base 125 comprising two insulating portions, a shell contact having a portion extending between said insulating portions, a contact carried on said base for detachably engaging another contact, and means for holding said 130 contact on said base and said insulating por-

tions together comprising a screw extending through both said insulating portions.

13. A contact device comprising an insulating member having a center recess and 5 an annular recess surrounding said center recess, a second insulating member, a center contact supported thereby, a shell contact surrounding said second insulating member, a contact in said center recess electrically connected to said center contact, and 10 a contact in said annular recess electrically connected to said shell contact.

14. A contact device comprising an insulating member having a center recess and 5 an annular recess surrounding said center recess, a second insulating member, a center contact supported thereby, a shell contact surrounding said second insulating member, a contact in said center recess electrically connected to said center contact, and 10 a contact in said annular recess integral with said shell contact.

15. A contact device comprising an insulating member having a center recess and 25 an annular recess surrounding said center recess, a second insulating member, a center contact supported thereby, a shell contact surrounding said second insulating member, a contact in said center recess electrically connected to said center contact, a contact in said annular recess electrically connected to said shell contact, and a binding terminal carrying portion having an annular contact for entering said annular recess to engage the contact therein, and a contact for entering said center recess to engage the contact therein.

16. In a connector an insulating base having a center recess, and an annular recess surrounding said center recess, contacts in said recesses, an insulating member, binding

terminals carried thereby, contacts electrically connected to said binding terminals for extending into said recesses and engaging the contacts therein, the contacts in said center recess having curved inter-engaging portions for holding the contacts together, and the contacts in the annular recess having straight axially extending inter-engaging surfaces whereby small clearance is required in the annular recess. 45 50

17. In a connector an insulating member, a pair of binding terminals carried thereby, a second insulating member having a screw threaded opening therein, of a size to grip the insulation of an insulated cord carrying two insulated conductors, said two members being provided with coöperating means for gripping the insulation of the individual conductors, and means for drawing the two insulating members toward each other without relative rotation therebetween to clamp the individual conductors. 55 60

18. In a connector an insulating member, a pair of binding terminals carried thereby, a second insulating member having a screw threaded opening therein of a size to grip the insulation of an insulated cord carrying two insulated conductors, said two members being provided with coöperating 65 70 means for gripping the insulation of the individual conductors, and means for drawing the two insulating members toward each other without relative rotation therebetween to clamp the individual conductors, said 75 last means comprising a sheet metal shell having an abutment engaging one of said insulating members and having a screw threaded engagement with the other.

In witness whereof I have hereunto subscribed my name.

REUBEN B. BENJAMIN.
